ENGINE

Harold H. Timian, Detroit, Mich., assignor to
Continental Motors Corporation, Detroit, Mich.,
a corporation of Virginia

Application June 27, 1931, Serial No. 547,264

4 Claims. (Cl. 123—75)

This invention relates to internal combustion engines and has among its objects the provision of means for improving the general performance of the engine.

5 In engines of the hydrocarbon type it is common practice to employ a carburetor or other mixing device for vaporizing the hydrocarbon with air, the fuel mixture being then conducted to the engine cylinders for combustion. It has been determined that a certain portion of the hydrocarbon is carried along with the fuel mixture in liquid form, not being vaporized by the carburetor. Such a condition is generally prevalent with the present day fuels commonly used for 10 internal combustion engines, and is particularly pronounced in starting an engine as in cold weather or after the engine has been idle for a sufficient length of time to have cooled relative to its normal operating temperature. At such 15 times, and also to a lesser extent during the normal operation of the engine, the wet fuel particles including condensed portions of the fuel mixture tend to collect in the conduit intermediate the carburetor and cylinders, resulting in a sluggish action of the engine, difficulty in starting and generally undesirable engine performance.

My invention in its broad aspect is applicable to any type of hydrocarbon engine of the carbureted fuel mixture type. My present application is directed particularly to means for removing the wet fuel particles especially adapted for 20 poppet valve or like types of engines. This may be done in several ways although I prefer for 25 simplicity and convenience to collect the wet fuel particles by suction. Thus I may remove the wet fuel particles by suction derived by the engine piston, the wet particles being conducted from the fuel mixture supply conduit to a suitable 30 point of disposal, preferably into the cylinder separately from the supply conduit. By such a general engine construction I have greatly improved the starting ability of the engine as well as overcoming the sluggish action of the engine.

More particularly my present invention is adapted for use with an engine employing a 35 downdraft carburetor and associated manifold structure and more particularly constructed to drain the wet fuel from the lowest point in the fuel mixture conducting system.

One important application of my present invention relates to poppet valve or like types of engines as distinguished from sleeve valve engines. I have illustrated my invention in connection with a typical well known type of engine

known as the L-head type, although as aforesaid my invention is also applicable to other general types of engines and valve arrangements. It is not my purpose therefore to limit my invention except as specifically recited in the appended claims.

In the accompanying drawing in which like reference characters indicate corresponding parts:

Fig. 1 is a sectional view through one of the 10 cylinders and intake manifold of a typical poppet valve engine, illustrating my invention, and

Fig. 2 is a similar sectional view of the engine with the piston completing the intake stroke.

Referring to the drawing reference character 15 10 illustrates the engine cylinder block having cylinders 11 jacketed at 12 for circulation of a cooling fluid. The cylinder ends are closed by the usual cylinder head 13 to provide a valved combustion chamber 14. The usual intake and exhaust valves may be provided for each chamber 14, the intake valve being illustrated at 15 controlling intake port 16. The intake port 16 communicates with the fuel mixture supply manifold 17 through cylinder intake passage 18 it being 20 understood that branch passages 18 are provided singly or in groups for the various intake ports of the various cylinders of the engine. 19 represents a conventional carburetor for supplying carbureted commercial gasoline or other hydrocarbon to the intake manifold. The engine thus far described is in the main conventional and well known, further description of the details being unnecessary for the purpose of a full and comprehensive disclosure of my invention. Pref- 25 erably I find that it is preferable in many instances to employ a downdraft carburetor, in which case the manifold structure 17 is provided with a fuel mixture conducting portion 17a extending downwardly from the carburetor 19 to 30 the fuel mixture distributing chamber 17b a plurality of manifold branches including port runner portions 17c communicating with the said fuel mixture distributing chamber 17.

Each cylinder intake passage 18 slopes downwardly and inwardly of the engine cylinder block 10 and thence upwardly to the intake port 16. In an engine employing an updraft carburetor excessive accumulations of wet fuel may be readily drained into the carburetor for subsequent use, but in an engine employing a down-draft carburetor, it is not possible to drain off excessive accumulations in this way. The removal of wet fuel accumulations in an engine employing a downdraft carburetor is more vital than in 55

engines employing an updraft carburetor in order to provide efficient engine operation with a minimum of fuel consumption. A practical engine employing a downdraft carburetor is more or less 5 dependent on the elimination of excessive wet fuel accumulations in the fuel mixture conducting means.

In order to collect or concentrate the unvaporized and condensed particles of hydrocarbon and 10 fuel mixture passing from the carburetor 19 to the intake ports 16 I provide one or more traps 20 for each cylinder conduit 18. The floor of the 15 conduit 18 is sloped as specified above so that any wet particles tending to form or collect in this portion of the fuel mixture supply system will drain by gravity toward and into the trap 20. The 20 wet particles collected in the trap 20 may be disposed of as desired, it being one feature of my invention to provide means for conducting the 25 wet particles by suction into one or more cylinders of the engine. Thus the trap 20 communicates with a port 21 in the cylinder wall, a suitable 30 conduit 22 conducting the wet particles from the trap 20 to the port 21. Interposed at a convenient point in the drain system is a valve assembly 35 consisting of a check valve 23 yieldingly urged to its seat by a spring 24.

The port 21 is suitably timed with respect to 40 the engine piston 25 so as to be uncovered by the downward travel of the piston, preferably toward the end of the downward stroke of the piston.

In operation, assuming the piston 25 as in Fig. 45 1 on its downward intake stroke, the port 21 is preferably covered by the piston during its initial downward travel and the valve 23 is seated by reason of spring 24. As the intake stroke continues the piston uncovers port 21 as in Fig. 2 and the suction within the engine cylinder 50 created by the piston will act in conduit 22 to unseat the valve 23. Thus, the wet fuel mixture particles, drained by the intake system proper and collected in trap 20 will be removed from the intake system and passed through the conduit 22 into the engine cylinder. On the upward compression stroke and upward exhaust stroke of the piston, the pressure in the cylinder and in conduit 22, during that portion of the stroke when port 21 55 is open to the cylinder, will act with spring 24 to keep the valve 23 seated. Similarly when the explosion or working downward stroke of the piston takes place the cylinder pressure will keep the valve 23 seated. By varying the position of port 21 with respect to the piston stroke the degree and duration of suction exerted in conduit 22 may be varied as desired under the circumstances.

By reason of my invention the wet fuel particles are removed from the fuel intake system between the carburetor and cylinder intake ports as fast as they accumulate. Any wet particles 60 collecting between successive intake strokes for any cylinder will build up in the trap 20 at the rear of valve 23 and will be removed at the next suction stroke. The relatively small capacity of the conduit 22 with respect to the intake manifold 17 is not sufficient to interfere with the normal functioning of the engine intake.

I prefer to provide a conduit 22 for each engine cylinder in order to obtain the same conditions of operation for each engine cylinder although 65 if desired for simplicity the wet fuel particles may be conducted from the intake system to any one or more cylinders.

Preferably the conduit or passage 22 lies in a vertical transverse plane through the engine 70 containing the intake valve axis, said engine cyl-

inder block being constructed to provide an annular recess or pocket 26 surrounding the valve guide 27, thereby facilitating the positioning of said sump or settling basin 26 at the lowest point in the fuel mixture conducting system. 5 The wet fuel particles are thus drained from the intake passage 18 as well as from the manifold structure 17 and due to the frequent actuation of the check valve 23 very little wet fuel is allowed to accumulate in the sump 20. The 10 check valve assembly is preferably located in conduit or passage 22 intermediate the cylinder and pocket 26. Preferably this valve assembly consists of a sleeve 23' in which the ball valve 23 and spring 24 are supported, said sleeve being 15 arranged to fit within said passage or conduit 22.

Although I have illustrated but one form of my invention, and have described in detail but a single application thereof, it will be apparent to those skilled in the art to which my invention pertains that various modifications and changes may be made therein without departing from the spirit of my invention or from the scope of the appended claims.

What I claim as my invention is:

1. In an internal combustion engine, a cylinder, a conduit for supplying a vaporized hydrocarbon to the cylinder and including a cylinder intake passage, a second conduit communicating with the cylinder independently of the first said conduit for removing therefrom unvaporized portions of the hydrocarbons, valve means associated with said cylinder intake passage for controlling admission of the hydrocarbon to the cylinder, a valve guide supporting said valve means, 35 said engine having an annular pocket surrounding said valve guide and communicating with said passage, said second conduit communicating with said pocket.

2. In an internal combustion engine, a cylinder, a conduit for supplying a vaporized hydrocarbon to the cylinder and including a cylinder intake passage, a second conduit communicating with the cylinder independently of the first said conduit for removing therefrom unvaporized portions of the hydrocarbons, valve means associated with said cylinder intake passage for controlling admission of the hydrocarbon to the cylinder, a valve guide supporting said valve means, 45 said engine having an annular pocket surrounding said valve guide and communicating with said passage, said second conduit communicating with said pocket and located in a transverse plane through the engine containing the valve and valve guide axis.

3. In an internal combustion engine, a cylinder, a conduit for supplying a vaporized hydrocarbon to the cylinder and including a cylinder intake passage, a second conduit communicating with the cylinder independently of the first said conduit for removing therefrom unvaporized portions of the hydrocarbons, valve means associated with said cylinder intake passage for controlling admission of the hydrocarbon to the cylinder, a valve guide supporting 60 said valve means, said engine having an annular pocket surrounding said valve guide and communicating with said passage, said second conduit communicating with said pocket, and a check valve associated with said second conduit.

4. In an internal combustion engine, a cylinder, a conduit for supplying a vaporized hydrocarbon to the cylinder and including a cylinder intake passage, a second conduit communicating with the cylinder independently of the first said 75

conduit for removing therefrom unvaporized portions of the hydrocarbons, valve means associated with said cylinder intake passage for controlling admission of the hydrocarbon to the cylinder, a valve guide supporting said valve means, said engine having an annular pocket surround-

ing said valve guide and communicating with said passage, said second conduit communicating with said pocket, and a check valve assembly located in said second conduit intermediate the cylinder and said pocket.

5

HAROLD H. TIMIAN.
